METHOD AND APPARATUS FOR UNITING
PRINTING WEBS

David J. Seaman and Howard H. Metcalf, Battle Creek, Mich., assignors, by direct and mesne assignments, to Seaman-Metcalf Incorporated, a corporation of Michigan

Application February 25, 1935, Serial No. 7,958

37 Claims. (Cl. 270—32)

The present invention relates to improvements in a method and apparatus for uniting associated printed webs in the production of newspapers, magazines, signatures, etc.

5 All readers of large size daily newspapers have experienced the difficulties connected with the handling thereof during the course of reading. The double sheets are freely folded one within the other and the single sheets are loosely inserted between a folded double sheet. As a result, it is extremely bothersome and awkward to fold back a leaf of the newspaper because of its tendency to either fall away from the remaining sheets or its failure to hinge about any definite fold line. 10 Also when a leaf of an outer sheet is turned back, that sheet becomes disassociated with the remaining sheets. Moreover, this loose folding of the sheet, one within the other, permits the sheets to become misplaced and lost which is exceedingly 15 trying upon the patience of the reader.

In magazines and weekly magazine sections of newspapers, the above mentioned difficulties have been overcome by stapling or stitching the printed sheets or webs along the fold line. However, in 25 the case of the daily newspaper, the lateness at which it goes to press and the speed at which the webs are printed, associated and folded, delivered and placed in the hands of the reader is such as to render impractical all heretofore known methods 30 of printed sheet or web uniting or binding employed in the production of magazines, signatures, etc.

The patented art discloses the application of an adhesive to the fold line of the web and even 35 stapling at press speed. However, in the disclosed methods of adhesive application, it is necessary to provide adhesive applying equipment for each web over a four page issue which renders such method impractical in view of the size of present 40 day issues to say nothing of the difficulties involved in attempting to apply an adhesive to the fold line of a web prior to the forming and trimming operation. In addition, to our knowledge no stapling mechanism heretofore designed or 45 suggested is capable of performance at present day press speeds.

When the uniting of associated printed webs is considered, particularly with reference to a daily newspaper press, it is a prerequisite that the uniting operation take place at press speed without interference or affect upon the operation or efficiency of the press. By necessity, newspapers are printed upon low grade paper with little resistance to abuse of any character, and speed of 50 delivery of the printed web is of major import-

tance. Thus any practical method of uniting must not be detrimental to the web or resist its high speed feed.

Thus it becomes an object of the present invention to provide improvements in a method and apparatus for uniting associated printed web capable of being applied to present day high speed presses.

Another object resides in a novel method and apparatus for uniting the running webs of a printing press after association of the same preparatory to forming.

Another object resides in novel means for web uniting at press speed while the associated webs pass over the former.

10 Another object resides in the provision of novel means for perforating, piercing, or severing and applying an adhesive to the fold line region of associated printing webs in synchronism with the speed of the press.

15 A further object resides in the provision of novel apparatus for supporting perforating, piercing, or severing and adhesive applying mechanism with reference to the former of the folding and delivering apparatus of the printing press.

20 A still further object is to provide mechanism for uniting associated printed webs at the fold line which may be readily installed upon presses now in use without interference with the operation or efficiency of such presses to any degree.

25 Other objects and advantages of the present invention residing in the construction and combination and arrangement of parts will be fully disclosed in the description to follow and should be readily apparent when considered in connection with the accompanying drawings wherein—

30 Fig. 1 is a front view of the former and web uniting mechanism,

Fig. 2 is a side view of Fig. 1,

Fig. 3 is a sectional view taken upon line 35 III—III of Fig. 1 showing the gear train,

Fig. 4 is a fragmentary side view of the web perforating roller,

Fig. 5 is a fragmentary side view of the adhesive applying roller,

Fig. 6 is a diagrammatical view of the adhesive applying mechanism,

Fig. 7 is a cross-sectional view of the former taken on line VII—VII of Fig. 2,

Fig. 8 is a fragmentary side view of one type 50 of web slitting roller,

Fig. 9 is a fragmentary side view of one type of adhesive applying roller to be used in connection with the roller shown in Fig. 8,

Figs. 10 and 11 are fragmentary sectional views 55

taken on lines X--X and XI--XI of Figs. 8 and 9, respectively,

Fig. 12 is a broken fragmentary sectional view taken along the fold line of the superimposed web showing the perforating and adhesive applying operations being performed.

Fig. 13 is a diagrammatical showing of a modified arrangement in which the perforations and adhesive applying operations take place beyond the former, and

Figs. 14 to 17, inclusive, are modified showings of several possible perforating arrangements along the fold line region of the printed webs.

When generally considered, the present invention resides in treating or processing associated webs or webs to be associated to permit the application of an adhesive or the like from one or both sides of the webs in their associated state to unite one to the other. In the preferred form of the invention, the treatment or processing of the printed web is deferred until some stage in the travel of the web between the printing operation and the delivery at which the region of each web defining or to define the fold line is established.

Ordinarily, the webs are most conveniently treated in their associated state at the former or thereafter. Preferably, in the treating or processing of the web, openings are provided in the body of the associated webs along or adjacent the fold line either before, after or during the folding operation. These openings may be formed by perforating with the bodily removal of a portion of the stock, by piercing or severing, or in any other suitable manner. Adhesive or the like is then applied to or inserted into these openings enabling the adhesive to penetrate into the body of the associated webs to unite the webs one to the other in the region of the fold line. In the several embodiments illustrated in the drawings,

the processing of the web to provide openings therein and the application of the adhesive is carried out at press speed; the peripheral speed of the perforating or piercing roll and the adhesive applying roll being substantially the same as the linear speed of the associated webs. As shown, the mechanism for providing the openings in the web and for applying the adhesive are driven by a common source and are timed together whereby the adhesive is applied only at the openings provided along the fold line. Obviously, other forms of mechanism for providing openings in the webs and applying adhesive are contemplated and fall within the scope of the present invention. In some forms of adhesive applying mechanism it may not be found necessary to time the operation thereof with that of the perforating or piercing mechanism, as for example, when the adhesive is sprayed or spread along the entire length of the fold line. The perforating, piercing, or severing of the associated web and application of the adhesive at the same stage and simultaneous therewith is also anticipated.

It also may be found feasible in some cases where the fold line can be definitely determined in advance, to perforate, pierce or otherwise treat or process each web along or adjacent the fold line region prior to web association and to thereafter treat the associated webs with adhesive along the fold line region. For example, the webs may be perforated along the region of the fold line at the paper mill.

Referring specifically to the drawings, we have illustrated a preferred form of our invention in connection with a well known type of printing press former which as shown has been slightly

modified to permit our method of web uniting to be carried out as the superimposed webs pass over the former. In order that the principles of the present invention may be practically applied to printing presses now in operation, it is necessary that the perforating and adhesive applying mechanisms be designed for installation in a locality free from interference with web guiding and delivering mechanisms and avoid all necessity of alterations in the operation, design and construction of the press. It is for this reason we have selected the former as the preferred locality for applying the web uniting mechanism to the press. However, we do not wish to limit the invention in its broad aspect to application at any particular location upon the press other than as defined by our appended claims.

In Figs. 1 and 2, the former 10 is pivotally supported from the press frame in the usual manner (not shown) and supported in its adjusted position by the brace rod 12. Supported in some suitable manner from the former, preferably upon opposite sides thereof, are web uniting mechanisms which in the illustrated embodiment takes the form of a perforating roller 14 and an adhesive applying roller 16. The perforating roller 14 coacts with a roller 18 through a slot 19 in the former to perforate the superimposed webs 19 along the region of the fold line. As more clearly shown in Fig. 4, the perforating roller 14 has a serrated surface defining punching or severing teeth 20 which provide longitudinally spaced openings in the webs as they pass over the former 10. In the preferred form of the invention, the adhesive applying roller 16 has 35 peripheral teeth 21 corresponding, generally, to those of the perforating roller 14 and is driven in timed relation with the perforating roller 14. The adhesive applying roller 16 is supplied with a suitable adhesive by a transfer roller 22. As 40 should be readily apparent, by proper timing the teeth 21 of the roller 16 will be projected into the openings of the webs produced by the roller 14, to penetrate the laminated body of the webs with the adhesive. A slot 26 is provided in the 45 form to receive the roller 16 through the underside thereof. To avoid any deflection of the web by the roller 16 and to assure proper projecting of the portion 24 into the body of the webs, a spring tensioned roller 28 is provided in alignment with the roller 16 and adapted to cooperate therewith to define the path of travel of the webs.

One convenient arrangement for driving the rollers 14 and 16 in timed relation and in coordination with the linear speed of the webs is as 55 follows: The usual roller 30 at the top of the former is equipped with a sprocket 32 and through a suitable chain 34 drives the transverse shaft 36 by being passed over the sprocket 38 carried at one end thereof. Shaft 36 extends beneath the 60 former and carries a gear 40 at the opposite ends meshing with a gear 42 for driving the shaft 44 upon which the perforating roller 14 is located. The shafts 44 and 36 are located above and below the former 10, respectively, and are supported in suitable bearings located in the end brackets 46 and 48 secured to the former 10 through the beam 49. The roller 18 is carried upon and driven by the shaft 36 while the perforating roller 14 is carried upon and driven by the shaft 44. For 70 driving the adhesive applying roller 16 in timed relation with the perforating roller 14, a gear 52 located upon the shaft 36 meshes with a gear 54 located upon the shaft 56 upon which the transfer roller 22 is keyed. The gear 54 in turn 75

meshes with the gear 58 keyed to the shaft 60 upon which the adhesive applying roll 16 is carried and driven. Also meshing with the gear 54 is a gear 62 upon the shaft 64 carrying the adhesive supply roller 68 operating in the adhesive pot 70. A scraper 12 of suitable construction is shown in connection with the roller 68 for regulating the adhesive being transferred to the applying roller 16. The gear train just described, together with the associated structure is all supported from spaced brackets 14 and 76, preferably supported from the under side of the former 10.

It should be apparent from the foregoing description that the perforating roller 14 and the adhesive applying roller 16 will be driven in definite timed relation. Moreover, it should also be apparent that by the proper selection of sprocket, gear and roller diameters, the tangential component of the peripheral speed of the perforating and adhesive applying rollers 14 and 16 may be coordinated with the linear speed of the superimposed webs. In this manner the webs may be treated as they pass over the former without any appreciable interference to their forward feed.

To enable initial feeding of new or additional webs over the former 10 through the web uniting mechanisms, structure is provided for removing both the perforating roller 14 and the tension roller 28 from the surface of the former 10. In the case of the roller 14, a shaft 78 journaled at opposite ends in bearings carried by the brackets 46 and 48 has eccentric portions 80 and 82 fixed thereto for rotation by the hand wheel 84. Opposite ends of the shaft 44, upon which the roller 14 is carried, are located in journaled blocks 86 slidably supported in guides 88. Springs 90 act to urge the shoulders 92 of the block 86 into engagement with the eccentric portions 80 and 82. By rotating the hand wheel 84 from the position shown in Fig. 2, the springs 90 will act upon the block 86 to displace the roller 14 from the surface of the former 10. With respect to the pressure of roller 28, the same is rotatably supported upon the arm 94 freely pivoted upon the rock shaft 96 journaled at opposite ends in the brackets 46 and 48. Fixed to the shaft 96 is an arm 98 in which is received for axial movement a push rod 100 connected at its lower end to the arm 94. A compression spring 101 acts against the arm 94 and a shoulder 102 of the rod 100 to resiliently urge the arm 94 and roller 28 against the webs 19 passing over the former 10. Adjustment nuts 103 upon the end of the rod 100 limits the axial movement of the rod 100 under the stress of the spring 101 and also acts to lift the rod 100 and arm 94 when the shaft 96 is rocked clockwise by the lever 105 fixed thereto. An adjustable pin 106 is employed to lock the lever 105 in a raised or lowered position as desired.

By way of refinement of construction the former 10 may be provided with a groove 108 along which any excess adhesive may flow to the former point 110 which is preferably heated by some suitable electric heater 112. The heating of the point 110 will prevent any accumulation of adhesive and all excess adhesive will be removed from the point of the former by the fold line of the lowermost web. Also, if desired, the conventional pinch rolls 114 and 116 may be provided with plain cylindrical sections 118 in the region of the fold line of the webs and scrapers 120 and 122 employed to remove any accumulation of ad-

hesive. For the sake of clarity, the scraper 122 is not shown in Fig. 2.

In Fig. 6 is a more or less diagrammatical showing of the adhesive applying mechanism. As will be apparent from a consideration of Fig. 12, the adhesive is applied to the openings in the web by the side walls of the teeth 21. One proposed manner of accomplishing this is to provide the transfer roller 22 with a grooved periphery 124 which straddles the periphery of the supply roller 68 and wipes the adhesive upon the side of the teeth 21 which pass through the groove. The scraper 12 is shown shaped to remove excess adhesive from the sides and periphery of the supply roller 68.

A modified structure for providing openings in the webs 19 is shown in Fig. 8 in which case the webs are slit or severed at spaced intervals by knife portions 126 defined about the periphery of the rotary roller 128. With this type of roller the cooperative roller corresponding to the roller 18 would take the form of a plain cylindrical hardened steel roller as in well known practice. In Fig. 9 is shown a modified adhesive applying roller 130 having teeth 132 of a design to enter the opening provided in the webs 19 by slitting action of the knife portions 126 of the roller 128. In Figs. 10 and 11, cross-sectional views of the rollers 128 and 130 are shown.

In Fig. 12 an attempt has been made to illustrate the perforating and adhesive applying operation as carried out upon the webs 19 as they pass over the former 10. The teeth 20 of the perforating roller may be of any desired shape such as cylindrical as shown. Upon being projected through the webs 19 from above, the opening defined portions 134 of each web will be slightly deflected downwardly by the perforating operation as shown. This has a tendency to fan or slightly separate the superimposed web portions defining the openings. When the openings in the webs have traveled from the perforating roller 14 to the roller 16, a tooth 21, which is shown as slightly conical, carries the adhesive upwardly into the opening and the slightly fanned downwardly deflected condition of the web portions 134 enhance the transfer action between the engaging surface. The result is that the adhesive is effectively transferred from the tooth 21 to the opening defined portions 134 of the webs and as flows between the adjacent webs in the immediate locality of the opening to unite the webs to one another. The opening 140 is shown in Fig. 12 as having a coating of adhesive 142 uniting the opening defined portions 134 of the webs and as penetrating into the laminated body between adjacent webs as at 144. Although we do not wish to limit ourselves to perforating from one side of the webs and applying the adhesive from the other side, it is considered an important feature of the invention. Satisfactory results, however, may be obtained by having the perforating and adhesive applying rollers located upon the same side of the webs. In addition, we anticipate the perforating and application of adhesive into the openings as a single step performed by the same instrumentality.

The web uniting mechanism in Figs. 1 and 2 is shown as driven from the roller 30 at the top of the former 10. In some cases it may be found more convenient to drive the uniting mechanism from some other power take-off synchronized with the operation of the press. Moreover, individual synchronized drives may be found more

desirable for the perforating and adhesive applying mechanisms in some installations.

A modified arrangement of the perforating and adhesive applying mechanism is diagrammatically shown in Fig. 13. The perforating roller 146 and the adhesive applying roller 148 are shown located beyond the former 150. Conventional rollers 151 at points of the former and pinch rollers 152 are shown located above and below the web uniting mechanism. As an embodiment modified from that shown in Figs. 1 and 2, the perforating and adhesive applying rollers are both shown located upon the same side of the webs. With the arrangement shown in Fig. 13, the perforations of the webs along the region of the fold line will not be performed until after the associated webs have been longitudinally folded by passage over the former 150.

In Figs. 14 to 17, inclusive, several of the numerous possible types and arrangements of the openings are illustrated. Referring to Fig. 14, the associated webs 19 are shown perforated by a circular punch providing spaced groups of openings 154. In Fig. 15 perforations similar to those shown in Fig. 14, are shown in staggered groups 156 offset upon opposite sides of the center line of the webs 19. This arrangement has the advantage that the webs are not weakened along the fold line portion passing over the nose of the former. If it is considered desirable to be able to conveniently and readily remove a page of a newspaper, for example, having the sheets united as heretofore described, the webs 19 may be perforated along the fold line to provide openings 158, as shown in Fig. 13, to receive the adhesive, and in addition be perforated along lines 160 and 162 upon opposite sides of the fold line to permit any desired page to be readily removed. The openings 158 as shown are elongated slits such as would be produced by the roller shown in Fig. 8. In Fig. 17, the openings 164 are shown as uniformly spaced along the fold line of the webs 19 such as would be produced by the perforating roller shown in Fig. 4.

Obviously, the structure of the perforating roller or equivalent structure will vary materially depending upon the type and arrangement of openings desired in the associated webs. In the illustrated embodiment both the perforating and adhesive applying mechanisms are of a rotary type. We fully anticipate such mechanism taking other forms and we include as within the scope of the present invention all such variations in construction as should readily occur to those skilled in the art which is capable of being synchronized with the operation of the press and travel of the webs and capable of providing openings in the associated webs and the application of an adhesive thereto at press speed and without interference to web travel, and is capable of providing openings in the associated webs and the application of adhesive thereto at press speed without interference to the web travel without being synchronized with the travel of the webs.

We wish to have it understood that the term perforate and perforating roller as used in the description and claims is to be taken in its broadest sense. It is intended to be generic to all structures for providing openings in the webs whether the webs be punched, pierced, slitted, severed, or ruptured, or whether or not stock is removed from the webs.

Having described our invention what we believe is patentable and desire to protect by Letters Patent is:

1. A method of uniting associated webs in a newspaper press or the like comprising the step of uniting longitudinally spaced portions of webs having a fold line region at press speed while in a superimposed state by forcibly penetrating the body of the webs with an adhesive applied to the webs in the region of the fold line. 5

2. A method of uniting superimposed webs of material during movement of the webs comprising the steps of providing openings in the body of the webs and then applying an adhesive into said openings of sufficient consistency and quantity to unite the several webs one to the other in the locality of said openings, said steps being carried out in relation to the movement of the webs. 10 15

3. A method of uniting associated webs in a newspaper press or the like comprising the step of uniting with an adhesive longitudinally spaced portions of the superimposed webs in the region of the fold line at the time the webs pass over the former. 20

4. A method of uniting associated printed webs of a newspaper press and the like at press speed comprising the steps of providing openings in the associated webs and forcibly directing an adhesive into said openings for uniting the webs to each other. 25

5. A method of uniting superimposed webs of material comprising the steps of providing openings in the body of the web and then applying an adhesive into said openings of sufficient consistency and quantity to unite the several webs one to the other in the locality of said openings, said steps being carried out during movement of the webs. 30 35

6. A method of uniting associated longitudinally folded printed webs at press speed comprising the steps prior to folding of providing openings in the associated webs in the region of the fold line and then directing an adhesive into said openings for uniting the webs to each other. 40

7. A method of treating associated longitudinally folded printed webs to unite the same along the region of the fold line comprising the steps prior to folding of superimposed traveling webs 45 to define a laminated body structure, providing openings in said body structure at spaced points along the region of the fold line and coordinated therewith penetrating said body with an adhesive applied through said openings whereby each web 50 is united to the adjacent web in the region of said openings.

8. A method of treating associated longitudinally folded printed webs to unite the same along the region of the fold line comprising the steps prior to folding of superimposing traveling webs 55 to define a laminated body structure, providing spaced openings in said body without interference with the movement thereof, and then directly applying an adhesive into said openings. 60

9. A method of uniting associated longitudinally folded printed webs at press speed comprising the steps prior to folding of superimposing a plurality of printed webs, treating at press speed the laminated body defined by said webs to provide openings therethrough, spaced longitudinally of the webs along the region of the fold line, and then at press speed penetrating said body with an adhesive directed through said openings. 65 70

10. A method of uniting associated longitudinally folded printed webs at press speed comprising the steps prior to folding of superimposing webs, each having openings therein in the region of the fold line adapted to at least partially regis- 75

ter with the openings in the adjacent webs, and while the superimposed webs are traveling at press speed directing an adhesive into said openings to unite the webs to each other.

5 11. A method of uniting superimposed longitudinally folded printed webs at press speed comprising the steps prior to folding of providing openings in each web in the region of the fold line adapted to at least partially register with 10 openings in the adjacent webs, and then directing an adhesive into said openings for uniting the webs to each other.

12. A method of penetrating the body of superimposed webs of material with an adhesive to 15 unite the webs to each other comprising the steps of providing openings in each web, and then with said webs arranged to bring said openings into at least partial register penetrating the body of 20 said webs with an adhesive directed through said openings of sufficient consistency and quantity to unite the several webs one to the other in the locality of said openings.

13. A method of penetrating the body of superimposed webs of material with an adhesive to 25 unite the webs to each other comprising the steps of providing openings in each web, then with said webs arranged to bring said openings into at least partial register penetrating the body of 30 said webs with an adhesive directed through said openings of sufficient consistency and quantity to unite the several webs one to the other in the locality of said openings, and applying a pressure 35 against the webs in the region of said openings to direct said adhesive between the webs in the locality of said openings.

14. A method of uniting printed webs in newspaper presses or the like comprising the steps of providing openings in the webs from one side of the web and then applying adhesive to said openings of sufficient consistency and quantity to unite the several webs one to the other in the locality of 40 said openings from the opposite side of the web.

15. In combination with the former of a printing press, means supporting said former for adjustable movement, web treating means supported from and contiguous with the web guiding surface of the former and adapted to act upon the webs passing over the former to provide 45 spaced openings therein along the region of the fold line, said means being adjustable as a unit with said former.

16. In combination with a former of a printing press, bracket structure supported from the former, driving mechanism carried by said bracket and located upon opposite sides of said former, and web perforating and adhesive applying means located upon opposite sides of said former and 50 operated by said driving mechanism.

60 17. In a printing press, a former having a point over which the printed webs are longitudinally folded, adhesive applying means for applying an adhesive to the fold line region of the webs passing over said former, and means for heating said point to avoid an accumulation of adhesive thereon.

18. In a printing press, a former having a point 65 over which the printed webs are longitudinally folded, adhesive applying means associated with said former for applying an adhesive to the fold line region of the webs passing over said former, means defined in the surface of said former for conducting excessive adhesive from said first means to said point, and means for heating said

point to avoid an accumulation of adhesive thereon.

19. In a printing press, a former over which the printed webs are passed and longitudinally folded, an opening in the face of said former over which the fold line region of the webs pass, and web perforating and adhesive applying means acting through said opening for treating said webs. 5

20. In a printing press, a former over which the printed webs are passed and longitudinally folded, longitudinally spaced openings in the face of said former, and web perforating and adhesive applying means acting through said openings for uniting said webs. 10 15

21. In a printing press, a former over which the printed webs are passed and longitudinally folded, longitudinally spaced openings in the face of said former, and means located above and below said former and acting through said openings 20 for perforating said webs from one side and for applying adhesive to said webs from the other side.

22. In a printing press, the combination with a former having a nose over which the printed webs are passed and longitudinally folded, means supporting said former for adjustable movement, of web treating mechanism supported by said former and adjustable therewith, said mechanism comprising means directly acting upon said webs 30 as the same pass along the former and prior to passing over said nose. 25

23. In a printing press, the combination with a pivoted former over which the printed webs are passed and longitudinally folded, means supporting said former for adjustable movement, of web treating mechanism supported by said former and adjustable therewith, said mechanism acting to unite said web in the region of the fold line, and a power take-off for said mechanism 40 concentric with the pivot for said former. 35

24. In a printing press, the combination with a former over which the printed webs are passed and longitudinally folded, of web treating mechanism supported by said former and adjustable therewith, said mechanism including web perforating means located on one side of said former and an adhesive applying means located upon the other side of said former, and synchronized driving means for said first and second means. 45 50

25. In a printing press, the combination with a former over which the printed webs are passed and longitudinally folded, of web uniting mechanism entirely supported by said former and adjustable therewith, said mechanism including means for perforating said webs and means for applying an adhesive to said webs and synchronized operating means for said first and second means. 55

26. In a printing press, the combination with a former over which the printed webs are passed and longitudinally folded, of web uniting mechanism entirely supported by said former and adjustable therewith, said mechanism including rotary perforating means and rotary adhesive applying means, separate driving means for said first and second means, said driving means being synchronized. 60 65

27. In a printing press, the combination with means for supporting and guiding superimposed printed webs, of web uniting mechanism associated with said means, said mechanism including rotary means for providing spaced openings in said webs and rotary adhesive applying means for directing adhesive into said openings, and syn- 70 75

chronized driving means for said first means and second means.

28. In a printing press, the combination with means for supporting and guiding superimposed printed webs, of web uniting mechanism associated with said means, said mechanism including rotary means for providing spaced openings in said webs and rotary adhesive applying means for directing adhesive into said openings, a power take-off synchronized with the operation of the press, and synchronized driving means for said first means and second means driven from said power take-off.

29. A method of treating associated webs, to unite the same, comprising the steps of superimposing traveling webs to define a laminated body structure, providing openings in said body structure at spaced intervals, and penetrating said body with an adhesive applied through said openings of sufficient consistency and quantity to unite the several webs one to the other in the locality of said openings.

30. A method of treating associated webs to unite the same, comprising the steps of superimposing traveling webs to define a laminated body structure, providing openings in said body structure at spaced intervals, and uniting the several webs through said openings, solely by adhesive applied to the edges of said webs defining said openings.

31. As a step in the method of printing, uniting and folding webs in a printing press having a former and pinch rolls at the end of the former, the uniting of the associated webs at press speed along the region of the fold line by penetrating the body of the superimposed webs with an adhesive after they have become assembled at the head of the former and prior to their entry between the pinch rolls.

32. A method of treating associated webs to unite the same, comprising the steps of superimposing the webs to define a laminated body structure, providing an opening in said body structure by projecting an instrumentality through

45 from one side of the webs, and applying an ad-

hesive into said opening from the opposite side of the webs, said adhesive being of sufficient consistency and quantity to unite the several webs one to the other in the locality of said opening.

33. A method of treating associated webs to unite the same, comprising the steps of superimposing the webs to define a laminated body structure, providing openings in said body structure by projecting an instrumentality through from one side of the webs whereby the openings defining portions of said superimposed webs are deflected in the direction of the projection of said instrumentality, and applying an adhesive into said openings from the opposite side of the webs, said adhesive being of sufficient consistency and quantity to unite the several webs one to the other in the locality of said openings.

34. In a printing press, a former over which the printed webs are passed and longitudinally folded, longitudinally spaced openings in the face of said former, and means located above and below said former and acting through said openings for perforating said webs and applying adhesive into said perforations.

35. The combination with means for guiding a doubled web along its course, of means for perforating the web and means for applying an adhesive to the edges of the perforation of the web at the time and at the points at which it is perforated.

36. The combination with means for guiding webs along a course, of means for fracturing all of said webs at a plurality of points and means for applying an adhesive to the edges of the perforation of the fractured edges of the webs at the time of fracture.

37. The combination with a former for doubling a web longitudinally and a folding couple for folding the web transversely, of means for perforating the web at a point between the former and folding couple, and means for applying an adhesive to the edges of the perforation immediately after the puncturing operation.
